UNITED STATES PATENT OFFICE.

CHARLES BOOTHE STRACHAN, OF MASCOT, TENNESSEE, ASSIGNOR TO STRACHAN TUBE MILL COMPANY, A CORPORATION OF TENNESSEE.

PULVERIZING MILL.

Application filed May 25, 1925. Serial No. 32,797.

To all whom it may concern:

Be it known that I, CHARLES BOOTHE STRACHAN, a citizen of the United States of America, and a resident of Mascot, in the county of Knox, State of Tennessee, have invented new and useful Improvements in Pulverizing Mills, which invention is fully set forth in the following specification.

This invention relates to grinding or pulverizing mills of the character ordinarily used for crushing ore, stone or the like, and has for its object to provide a mill of such character and construction that the same may be operated by a minimum expenditure of power, producing a uniform character of product and a minimum amount of "slimes".

A further object of the invention is to provide for the ready separation of the ground product from that which has not been sufficiently pulverized and without complicating the apparatus by the provision of conveyors, separators and the like.

In the present invention, the ore or stone being acted upon which has not been crushed or pulverized to the desired condition is separated from the properly reduced material by centrifugal force, and this requires a high speed to be imparted to the mill, which speed, in turn, requires that the parts thereof shall be sufficiently massive not to have their grinding and separating operations interfered with by centrifugal action which is employed to separate the ground from the unground material.

With these objects in view, the invention consists of a strong, longitudinally extending cylindrical shell whose ends are closed by heads through one of which the material to be crushed is fed and through the other of which the material finds its exit. Said head pieces have on the interior sides thereof circular chambers whose interior walls are composed of perforated diaphragms firmly secured to the head pieces, and between these diaphragms are placed a series of unitary massive cylinders, one within the other, the diameters of the cylinders being such as to leave a very material spacing between the outer wall of the interior cylinder and the interior wall of the next adjacent cylinder, the innermost cylinder being preferably in the form of a solid cylindrical mass. These cylinders are of uniform length and are retained by the diaphragms of the respective head pieces so as to just

leave sufficient play for them to roll freely one within the other when the mill as a whole is rapidly revolved. The high speed at which the mill is revolved serves to throw the heavier unground particles outward from the center while the finely ground particles remain near the center, and adjacent to the center there are formed exits for the ground material.

Preferably, though not necessarily, the several cylinders have openings or perforations extending therethrough, to the end that the material under treatment will pass through said openings.

The inventive idea is illustrated in the accompanying drawings, which drawings are for the purpose of illustration only, and in which—

Fig. 1 is a central longitudinal section through a mill embodying the invention;

Fig. 2 is a vertical section on the line 2—2 of Fig. 1, looking in the direction of the arrow; and

Fig. 3 is a vertical section on the line 3—3 of Fig. 1, also looking in the direction of the arrow.

Referring to the drawings, in which like reference numerals indicate like parts throughout the several views, 4 is a strong cylindrical metal shell, the ends of which are closed by an inlet head 5 and an outlet head 6, said heads being held sufficiently against the ends of the cylinder by rods 7 passing through openings in the head and clamped in position by nuts 8, as will be readily understood by an inspection of Fig. 1. The inlet head 5 has a hollow cylindrical hub 9 which takes bearing in any suitable support, as a pier 10, the opening 11 through said hub 9 communicating with a feed hopper or case 12. Said head 5 has an annular inwardly extending flange 13 against the inner face of which is firmly mounted a massive diaphragm 14 provided with perforations 15, the construction being such as to leave an open cylindrical chamber 16, which, in turn, is in free and open communication with the channel 11 formed in the bearing portion 9. The diaphragm 14 is secured in position on the head 5 by means of suitable bolts 17 as will be readily understood from the drawings.

The outlet head 6 is provided with a central hub portion 18 within which is keyed or otherwise secured a shaft 19 taking bear-

ing in a suitable support or pier 20, and having thereon suitable means, as a pulley 21, for connection to a source of power.

Surrounding the head piece on the hub 18 5 is a cylindrical chamber 22 from which lead outwardly several openings 23, which openings preferably deliver into a discharge casing 24. The head piece 6 has an inwardly extending annular flange 25, to which is 10 bolted a diaphragm 26 provided with perforations 27.

Within the cylindrical casing 4 is a hollow massive cylinder 28, which latter cylinder is of less external diameter than the interior 15 diameter of the casing 4. The cylinder 28 is preferably of a unitary piece of metal and of just sufficient length to enable it to fit freely between the diaphragms 14 and 26, so that the cylinder 28 rests with its entire 20 weight on the bottom of the interior of casing 4. In like manner, a plurality of other cylinders 29, 30 and 31, each of sufficiently less diameter than the next exterior one to leave a free space when it rests upon the interior wall of the next exterior cylinder. 25 Within the cylinder 31 is placed a cylinder 32 which, as here shown, is a solid cylindrical mass of metal. All of the cylinders 28 to 32, inclusive, are of uniform length 30 and, as before stated, of sufficient length so that they are retained in place by the diaphragms 14 and 26 while at the same time being able to roll one within the other when the mill is revolved on its horizontal longitudinal axis.

In operation, the head pieces and casing are revolved at a high rate of speed, causing the cylinder 28 to roll within the casing 4, the cylinder 29 to roll within cylinder 28, 40 cylinder 30 to roll within the cylinder 29, cylinder 31 to roll within the cylinder 30, and the solid cylinder 32 to roll within the cylinder 31. As each of the cylinders is a unitary piece, and hence of great mass or 45 weight, this high rate of speed is maintained without any material effect in decreasing the crushing action between the adjacent surfaces of the respective cylinders. The material to be crushed is fed in through the 50 intake hopper 12 in such size as to readily pass through the openings 15 of the screen 14, and by reason of the unobstructed chamber 16, the larger and heavier particles will enter through the exterior perforations 15 55 while the smaller ones will pass through those nearer the center. When pieces of material enter into the openings between the respective cylinders, they are subjected to the great crushing weight of that cylinder 60 plus the cylinders within it, this weight being applied by the minimum consumption of power by reason of the fact that each cylinder rolls on approximately its own axis, and within the next adjacent exterior cylinder. 65 There is thus applied a very great

crushing or grinding weight with a minimum expenditure of power. By reason of the high speed the heavier, and hence insufficiently crushed, portions are thrown to the exterior where they can enter between the crushing rolls while the material which has been reduced to the finer desired condition will remain near the axis of the mill and will pass out through the openings 23 and the discharge casing 24. Moreover, the larger and hence more difficult pieces to crush being thrown to the exterior, they are subjected to the crushing effect of the combined weight of all of the cylinders 28-32, 75 inclusive. If desired, openings 33 may be 80 formed through the several hollow cylinders so as to permit the material to pass through said openings and into the space between the cylinders.

It will be observed that the entire mill is 85 formed of parts of great strength and massive weight which permits the same to be driven at a high rate of speed while at the same time taking ample advantage of the weight of the grinding or crushing elements 90 to efficiently perform this function, and this without the use of any elevators or other device. This is in marked contrast with previous structures in which the grinding or crushing elements are such that, if the machine were driven at a high rate of speed, 95 centrifugal action would reduce the crushing effect of the parts. Moreover, by reason of the fact that the central cylinder 32 is solid and that all the cylinders roll one 100 within the other, the large unground particles can pass through the mill only by entering between the cylinders at points above the lowermost of the exit openings and being subjected to the crushing action as the 105 cylinders roll one within the other. Furthermore, it will be observed that the exits from the mill are not in its axis, but on the contrary there are a plurality of exit openings between the axis of the mill and the 110 periphery of the chamber 26. The result of this is that centrifugal action throws the larger particles outward in said chamber, thereby crowding the finely ground particles toward the center where they find exit 115 through the openings 23 in the head 6. And for the same reason the larger particles in the exist chamber 22 are crowded back through the diaphragm and enter the open spaces between the rolls to be further 120 ground.

What is claimed is:—

1. The combination of a cylindrical casing, oppositely disposed heads secured to the respective ends of said casing, interiorly projecting annular flanges one on each head piece, a perforated diaphragm secured to each flange whereby a cylindrical chamber is formed in each head piece, and a series of cylinders of progressively decreasing di- 130

ameters within said casing rolling one within the other and of a length extending from diaphragm to diaphragm.

2. The combination of a cylindrical casing, two oppositely disposed head pieces having radial flanges bolted against the opposite ends of said casing and annular flanges projecting within said casing, a perforated diaphragm secured to each flange within the casing, and a series of cylindrical rollers of progressively decreasing diameters rolling one within the other and extending from one diaphragm to the other.

3. The combination of a head piece having an outwardly extending hollow hub and an inwardly extending annular flange, a bearing for said hub and a perforated diaphragm secured to said flange, with an oppositely disposed head piece having a hub portion and an interiorly extending annular flange, a perforated diaphragm secured to said last-named flange, an outwardly projecting shaft connected to said hub, a bearing for said shaft, a casing extending between said head pieces, and a series of cylinders of progressively decreasing diameters within said casing rolling one within the other and extending from diaphragm to diaphragm.

4. The combination of a cylindrical casing, a series of cylindrical rollers of uniform length and of progressively decreasing di-

ameters one within the other contained within said casing, the central roller being solid, and an exit head to said casing having openings successively presented below the axis of the casing during revolution.

5. The combination of a cylindrical casing, a chambered head closing the exit end of said casing, a perforated diaphragm forming the interior wall of said chamber, and a series of rollers of progressively decreasing diameters one within the other with their end portions abutting said diaphragm and closing the perforations of said diaphragm to the passage of unground material through an extended arc below the axis of said casing.

6. The combination of a cylindrical casing, a chambered head piece at each end of said casing, a perforated diaphragm forming the interior wall of the two chambers, and a series of cylindrical rollers of progressively decreasing diameters one within the other rolling within said casing with their ends abutting said diaphragms and closing the perforations in said diaphragms against the passage of unground material through an extended arc below the axis of said casing.

In testimony whereof I have signed this specification.

CHARLES BOOTHE STRACHAN.
